UNITED STATES PATENT OFFICE.

CHARLES GREEN, JR., OF LONDON, ENGLAND.

WATER-WASTE-PREVENTING CISTERNS.

1,106,141.

Specification of Letters Patent.

Patented Aug. 4, 1914.

Application filed January 8, 1914. Serial No. 811,091.

To all whom it may concern:

Be it known that I CHARLES GREEN, Jr., subject of the King of Great Britain, residing at 21 Northdown street, Kings Cross, London, England, have invented certain new and useful Improvements in Water-Waste-Preventing Cisterns and of which the following is a specification.

This invention relates to that type of flushing cistern which is fitted with a siphon outlet pipe and which is set in action by forcing air by means of a hand-operated compressor through a pipe on to a body of water contained in a vessel or case within the cistern, so that water is caused to rise above the siphon bend, the short leg of the siphon communicating with the interior of the case.

According to the present invention means are provided in this type of flushing cistern whereby the silent discharge of the water from the cistern is effected, that is the gurgling noise, usually produced on the approach of the termination of the discharge of water from the cistern is prevented. For this purpose the said case within the cistern is provided with a perpendicular pipe or tube, the upper end of which is arranged so as to be below the normal water level in the cistern, through which pipe, when the water leaves the inlet thereof free, air can enter, so that before the inlet of water from the cistern to the case becomes uncovered, air is admitted to the top of the case and the formation of a vacuum in the said case prevented, or the silencing may be effected or further insured by forming the plunger or piston, by which air is forced from the air chamber into the case, of tubular construction, the outer end of which piston when in use is closed by the finger by which the piston is forced inward, while when the finger is removed, the air chamber through the said piston is opened to the atmosphere, so that air at atmospheric pressure will enter the air tube and the top of the case, thereby preventing the formation of a vacuum in said case.

The invention will be further described with reference to the accompanying drawings, whereon,

Figure 1 is a vertical section showing a construction of flushing cistern according to my invention. Fig. 2 is a transverse section of the cistern shown at Fig. 1, and Fig. 3 is a horizontal section of a portion of the cistern taken on the line X—Y of Fig. 2.

Fig. 4 is a vertical section on a small scale illustrating a complete installation. Fig. 5 is a transverse vertical section, and Fig. 6 a front elevation showing an example of air compressing apparatus.

The flushing cistern 1 is of ordinary character, having a well bottom 2 and fitted with a siphon outlet pipe of a kind which is well known, composed of two legs 3 and 4, the leg 3 being fixed in an aperture in the base of the cistern.

The leg 4 of the siphon pipe is fitted at its end with what I have termed a vessel comprising in the construction illustrated an elliptical case 5, see particularly Fig. 3, into the top of which the leg 4 of the siphon enters and extends a short distance. The case 5 is open at its base, the diameter of the opening being slightly greater than the bore of the leg 4 of the siphon, and in the construction shown this opening is fitted with a cylindrical ferrule 6, which extends a little above the interior surface of the base of the case 5 and extends for a distance below the base of the said case 5.

The cistern 1 is shown fitted with the usual ball valve 7 or it may be fitted with any convenient water supply regulating device.

Fixed to the top of the case 5 on one side of the siphon leg 4 and communicating with the interior of the said case is an air pipe 8, which extends above the cistern and is there connected to a pipe which is shown in the general view at Fig. 4 and marked 9. This extension air pipe passes to some convenient air compressing device, such as is shown at 10, Fig. 4, and an example of construction of which is illustrated at Figs. 5 and 6.

The device at Figs. 5 and 6 consists of a cylinder 11 which communicates with the extension air pipe 9, and contains a piston 12 having a barrel piston rod 13 open at its end, and the piston is maintained normally at the end of the cylinder, as shown at Fig. 5, by a spring such as 14. It will now be observed that the operator can place his thumb on the barrel piston rod 13, thereby closing the end of the tubular rod, and by pressure forcing the piston down the cylinder 11 and compressing the air in the air pipe 8. This operation brings the siphon into action, and the water from the cistern 1 passes down the leg 3 of the siphon, and the operator, upon removing pressure from the barrel piston rod 13, the piston is

brought back to the position shown at Fig. 5, and air at atmospheric pressure then passes through the barrel piston rod 13, cylinder 11, pipe 9, 8, into the top of the case 5, and thus prevents the formation of a vacuum in the said case 5 upon the approach of the termination of the discharge of water from the cistern.

I have found that the apparatus so constructed is effective and comparatively silent in operation, but to improve the action as regards the degree of silence, which in such apparatus is of very considerable importance, I attach to the top of the case 5 (or vessel) a pipe 15 communicating at its lower end with the interior of the case 5 at the top part thereof, and extending upward and having its upper end, which is preferably bent over below the normal water level which is indicated in the drawings, and I have found that by this addition any noise which might occur just before the inlet 6 became uncovered by the water leaving the cistern is entirely prevented.

25 What I claim as my invention and desire to secure by Letters Patent is:—

1. In a flushing cistern of the type specified, the combination of a fixed bent siphon pipe within said cistern, said siphon having a long discharge leg and a short inflow leg, an inner case or vessel fixed at the lower end of said short leg, said lower end extending through and to a short distance below the top of said inner case, an air pressure pipe communicating with the interior of and at the top of said case, means to force air through said air pressure pipe into said case, and a pipe extending perpendicularly from

the top of said case and communicating with the interior thereof, the free upper end of this pipe being normally closed by water in the cistern.

2. In a flushing cistern of the type specified; the combination with a fixed bent siphon pipe within said cistern, said siphon having a long discharge leg and a short inflow leg, of an inner case or vessel at the lower end of said short leg, said lower end extending through and to a short distance below the top of said inner case, an air pressure pipe communicating at one end with the interior of the top of said case, an air receiving chamber at the other end of said pipe, an air compressing piston adapted to be moved in said chamber to compress air therein and force air through said air pressure pipe to said case, a spring to normally maintain said piston at one end of said chamber, a hollow piston rod connected to and passing through said piston to normally admit air to said chamber, the entrance of air through said piston to said chamber being adapted to be stopped by the hand of the operator when moving said piston within said chamber, and a pipe extending perpendicularly from the top of said case and communicating with the interior thereof, the free upper end of said pipe being normally closed by water in said cistern.

In witness whereof I have hereunto set my hand in the presence of two witnesses.

CHARLES GREEN, JUNR.
